CAR COUPLER

George M. Murphy, Columbus, Ohio, assignor
to The Buckeye Steel Castings Company,
Columbus, Ohio.

Application September 4, 1931, Serial No. 561,243

5 Claims. (Cl. 213—145)

This invention relates to improvements in car couplers, and more particularly to means for restoring couplers to gauge.

Couplers in service are continually checked for "gauge", and due to present day service conditions of longer trains and heavier cars, it has been found that couplers reach the gauging limit in a short period of time. By the term "gauge" is meant the distance in a horizontal plane between the nose of the knuckle and the guard arm face of the coupler head. When the gauge passes these points, the coupler must be removed from service according to the A. R. A. rules, and cars are not accepted in interchange with couplers 15 out of gauge.

Instead of scrapping the couplers when they are not badly worn, but out of gauge, it has been customary for railroads to restore the coupler to gauge by building up by means of welding the lock bearing face of the knuckle. Obviously, metal at this location places the nose of the knuckle closer to the guard arm face. Other means are also resorted to in order to restore the gauge, some railroads preferring to insert 25 a new knuckle known as a "compensating knuckle", which is so constructed that in a worn coupler, the nose will be closer than usual to the guard arm face. Others prefer to thicken the lock to restore the gauge.

30 The above methods will restore the couplers to gauge, but involve either the expensive operation of building up parts by welding, or the purchasing of new parts which are relatively expensive.

35 The primary object of the present invention is to provide an economical and effective means of restoring worn couplers of either the A. R. A. type "D" or "E", to gauge. Similar means for restoring couplers to gauge may be used on other 40 types of couplers.

With the foregoing object outlined and with other objects in view which will appear as the description proceeds, the invention consists in the novel features hereafter described in detail, 45 illustrated in the accompanying drawings, and more particularly pointed out in the appended claims.

In the drawings,

Fig. 1 is a top plan view partly in horizontal section of an assembled coupler head with my improved gauge restoring means in place.

Fig. 2 is a front elevation of the same.

Figs. 3, and 4 are vertical sectional views taken respectively on the lines 3—3 and 4—4 of Fig. 1, 55 and with the coupler knuckle and lock omitted.

Fig. 5 is an elevation of the improved shim which I have designed for gauge restoring purposes.

Fig. 6 is an edge view of the same.

Referring to the drawings, 10 is a conventional coupler head having the usual knuckle 11 mounted on a pivot pin 11a, and 12 is the customary lock. At 13 is my improved metal shim which can be inserted into the coupler head after the coupler is worn or just after the coupler has been in service long enough for the coupler and lock to take bearing, that is, it is unnecessary to wait until the coupler is out of gauge for the shim 13 to be inserted.

The shim, as best shown in Figs. 5 and 6, is of such shape that it can be readily inserted and retained in the coupler head, and I prefer to have it of such design that it can be inserted when the knuckle and lock are removed; at which time it can be introduced through the front opening 10a of the coupler head, and then be lowered into the lock hole 10b. Afterwards, it is raised to its proper position, as shown in Figs. 1 to 4 inclusive. Any suitable means may be employed for securing the shim in place, but I prefer to have it bear 80 against the coupler head by an inclined shoulder, as shown at 13a to prevent downward movement. The upper end of the shim is provided with a lip 13b which projects at right angles to the face of the shim and abuts against a vertical flange 85 13d within the head to prevent lateral movement. The lower end of the shim is provided with a depending lip or tongue 13c which can be bent outward and upward about the lower portion of the head to prevent the shim from raising 90 after it is in place.

By referring to Fig. 1, it will be noted that the knuckle 11 rotates about the pivot pin 11a, and when a pull is exerted on the nose 11b, the tail 11c of the knuckle bears against the lock 12, 95 which in turn would normally bear against the wall 10c of the coupler head. However, the shim 13 is positioned between the lock and this wall and functions as an abutment to limit the movement of the lock toward said wall, so that the nose 11b of the knuckle is prevented from moving away from the face 10d of the guard arm to as great an extent as it could if the shim was omitted.

It will also be noted from Fig. 1 that "A" indicates the normal position of the knuckle nose, the dotted line "B" the worn limit of the knuckle nose out of gauge, and the full line "C" the position of the knuckle nose when the shim 13 is applied to a coupler that is only slightly worn. When the 110

- knuckle is in position "B", or out of gauge, it may be brought to normal position, or when at position "A", it may be brought to position "C" by inserting the shim 13.
- 5 From Fig. 6 it may be seen that the upper end of the shim is tapered at 20, so as to reduce its thickness toward the top, and this is for the purpose of allowing clearance for the lock 12 when it is raised in the chamber 10e.
- 10 While I have disclosed what I now consider to be a preferred embodiment of the invention in such manner that the invention may be readily understood by those skilled in the art, I am aware that changes may be made in the details disclosed, without departing from the spirit of the invention, as expressed in the claims.
- What I claim and desire to secure by Letters Patent is:
1. A car coupler including a coupler head, a knuckle pivotally connected to the head, a lock arranged in the head and cooperating with the knuckle, said head being provided with an opening and a cavity, and a shim arranged in the head between said lock and a wall of the cavity for limiting swinging movement of the knuckle in one direction, said shim comprising a piece of metal which is substantially flat and of substantially triangular shape, the upper end of the shim being wider than the lower end of the same and being supported by portions of the inner surface of said head, said shim being provided with a lip at its upper end projecting substantially at right angles to a face of the shim, said lip cooperating with a projection on the coupler head to hold the shim in vertical plane.
  2. A car coupler including a coupler head having a cavity therein provided with projecting portions, a knuckle member pivotally connected to the head, a lock member arranged in the cavity and cooperating with the knuckle member, and a shim arranged in the cavity and cooperating with said members for limiting opening movement of the knuckle member in one direction, said shim comprising a piece of metal which is substantially flat and of substantially triangular shape, the upper end of the shim being wider than the lower end of the same, and said wider upper end resting on the projections in the cavity for holding the shim in said head, and means for holding the shim in a vertical plane.
  3. A car coupler including a coupler head, a knuckle pivotally connected to the head, a lock arranged in the head and cooperating with the knuckle, said head being provided with an opening, and a shim insertable into the head through said opening and being arranged between one side of the lock and an inner surface of the head for limiting the swinging movement of the knuckle in one direction, said shim comprising a piece of metal which is substantially flat and of substantially triangular shape, the upper end of the shim being wider than the lower end of the same and resting on portions of the inner surface of the head to prevent the shim from dropping downwardly in the coupler head, said shim being provided with a lip at its upper end projecting substantially at right angles to a face of the shim, said lip cooperating with a portion of an inner surface of the coupler head to hold the shim in vertical position.
4. A car coupler including a coupler head, a knuckle member pivotally connected to the head, a lock member arranged in the head and cooperating with the knuckle member, said head being provided with an opening, and a shim insertable into the head through said opening and arranged to cooperate with said members for limiting swinging movement of the knuckle member in one direction, said shim comprising a piece of metal which is substantially flat and of substantially triangular shape, the upper end of the shim being wider than the lower end of the same and being provided with a lip projecting substantially at right angles to the face of the shim, said lip engaging a portion of an inner surface of the head for holding the shim in vertical position, the edge of the shim opposite that from which the lip projects being provided with a shoulder resting on another portion of an inner surface of the head for limiting downward movement of the shim within the head.
5. A car coupler including a coupler head, a knuckle member pivotally connected to the head, a lock member arranged in the head and cooperating with the knuckle member, said head being provided with an opening, and a shim insertable into the head through said opening and so arranged as to cooperate with said members for limiting the swinging movement of the knuckle member in one direction, said shim comprising a piece of metal which is substantially flat and of substantially triangular shape, the upper end of the shim being wider than the lower end of the same and resting on portions of internal surfaces of the head for limiting downward movement of the shim within the head, said shim being provided at its upper end with a lip projecting substantially at right angles to a face of the shim and engaging a portion of the inner surface of the head for holding the shim in vertical position, and a bendable tongue projecting from the lower end of the shim and hooked about a portion of the head to limit upward movement of the shim.

GEORGE M. MURPHY.
